Primary Examiner — Cathron Brooks*Assistant Examiner* — Sharon S Oum(74) *Attorney, Agent, or Firm* — Morrison & Foerster LLP(57) **CLAIM**

We claim the ornamental design for an attachment for a hair appliance, as shown and described.

DESCRIPTION

FIG. 1 is a front perspective view of an attachment for a hair appliance showing our new design;

FIG. 2 is a rear perspective view thereof;

FIG. 3 is a front view thereof;

FIG. 4 is a rear view thereof;

FIG. 5 is a side view thereof;

FIG. 6 is a side view of the opposite side of FIG. 5; and, FIG. 7 is a top view thereof.

The broken lines shown in the drawings illustrate portions of the attachment for a hair appliance that form no part of the claimed design.
